UNITED STATES PATENT OFFICE.

JOHN H. WALKER, OF LEXINGTON, KENTUCKY.

TROLLEY.

SPECIFICATION forming part of Letters Patent No. 761,566, dated May 31, 1904.

Application filed July 29, 1903. Serial No. 167,466. (No model.)

To all whom it may concern:

Be it known that I, JOHN H. WALKER, a citizen of the United States, and a resident of Lexington, in the county of Fayette, in the State of Kentucky, have made certain new and useful Improvements in Trolleys, of which the following is a specification.

This invention is an improvement in trolley mechanism seeking to provide a novel construction whereby to secure a practically continuous copper conductor from the trolley-wheel to the motor, and to provide improvements in the connections between the harp, the branches of the conductor-wire, and the trolley-wheel, as will be more fully described; and the invention consists in certain novel constructions and combinations of parts, as will be hereinafter described and claimed.

In the drawings, Figure 1 is a side elevation, and Fig. 2 a top plan view, of the upper end of a trolley embodying my invention. Fig. 3 is a detail cross-section on about line 3 3 of Fig. 1. Fig. 4 is an elevation of the outer end of one of the carrier-blocks. Fig. 5 is an elevation of the outer end of the other carrier-block. Fig. 6 is an elevation of the inner end of one of the carrier-blocks. Fig. 7 is a perspective view of the shaft, the bushing-tube thereon, and the nuts and end washers for the shaft. Fig. 8 is a cross-section on about line 8 8 of Fig. 7. Fig. 9 is a sectional view of the shaft and its bushing, showing a somewhat different construction of bushing from that shown in Fig. 7. Fig. 10 is a detail perspective view of the upper end of one of the harp-prongs. Fig. 11 is a detail perspective view of one of the carrier-blocks.

By my invention I provide, in connection with the harp-prong and the trolley-wheel, the conductor-wire branches, having at their upper ends flat circular heads which fit against the inner faces of the harp-prongs and are so secured in such relation and in firm contact with the carrier-blocks for the wheel-supports as to secure the desired electrical connections.

In carrying out my invention I construct the harp with the prongs A, which are provided in their upper ends with the circular openings B, which are threaded at b to re-

ceive the threaded stems on the carrier-blocks, presently described. These prongs A are made in angle form in cross-section, as shown at A' in Fig. 10, thus producing an L-shaped cross-sectional prong, which operates to resist 55 any undue lateral springing of the prong and gives the prong the desired rigidity in the use of the invention.

The conductor-wire D leads to the socketed connection d, which is provided with the lug d', from which extend the branches D' of the conductor-wire. These branches D' are provided at their upper ends with the flat heads D'' in the form of continuous open rings, which are concentric with the openings B in the 65 prongs A and are lapped against the inner sides of said prongs, as shown in Figs. 2, 3, and 10, and are secured in such relation by the carrier-blocks, presently described. These flat heads D'' form conductor-bearings, against 70 which the carrier-blocks bear at their outer faces, thus providing broad flat conducting-surfaces between the carrier-blocks and the circular heads D'' of the branches of the conductor-wire, which conducting-surfaces extend throughout the outer faces of the carrier-blocks, as will be understood from Figs. 2, 3, 10, and 11 of the drawings.

The carrier-blocks C and C' are alike. These carrier-blocks are provided at their outer ends 80 with outwardly-projecting stems C'', socketed to receive the nuts on the wheel-shaft and threaded externally toward their outer ends at C''' to engage with the threads b in the harp-prongs, so that when the heads are threaded 85 to the position shown in Fig. 3 they will clamp the flat heads D'' of the conductor-wire branches tightly against the inner faces of the harp-prongs in order to secure perfect connection between the carrier-blocks and the 90 flat heads D'' in the use of the invention, as will be understood from Figs. 1, 2, 3, and 10. At their inner ends the projecting socketed stems C'' are preferably smooth, as shown at C'', and fit closely within the circular openings 95 in the flat heads D'' of the branches of the conductor-wire.

In their inner faces the carrier-blocks are provided with recesses for dry lubricant, such recesses being preferably, as shown in Fig. 6, 100

in the form of circular grooves F, which are eccentric to the shaft G, so that as the wheel revolves concentrically with the shaft G any tendency to form grooves in the ends of the 5 trolley-wheel, presently described, by reason of the grooves in the carrier-blocks will be avoided, as the end surfaces of the wheel moving over the eccentric grooves in the thrust-plates will tend to grind smooth at all times. 10 Therefore it is preferred to make the graphite recesses F eccentric, as shown in Fig. 6; but manifestly the form of said recesses may be varied, if desired.

The carrier-blocks are provided with openings C⁵ for the shaft G and have in their inner ends circular recesses C⁶ to receive washers E', of leather, rawhide, or the like, which fit on the shaft G and within the said recesses C⁶, as shown in Fig. 3.

20 The shaft G is threaded at its ends *g* to receive the end nuts H and H' and is provided with a projection G', fitting in a keyway in the steel bushing I, upon which the wheel J turns. In Fig. 9 the bushing is integral from 25 end to end, while in Fig. 7 and in Fig. 3 I provide at the ends of the steel bushing I copper rings I' to aid in conducting the current from the wheel J to the copper shaft G, so that the current is carried off directly from the wheel 30 to the carrier-blocks, as well as through the end rings I' in connection with the bushing I. It will be noticed that the steel bushing I will receive the wear of the wheel, while the rings I' will aid in carrying off the current.

35 The wheel J has an oil-cavity J' and a valve J², by which it may be supplied with oil. The wheel is also provided with a hub-tube K, which may be suitably secured in the wheel and is provided in its bore with grooves K', 40 supplied with graphite and operating upon the bushing I, which latter is keyed on the shaft G by the means before described. The shaft G extends through the opening C⁵ in the carrier-blocks and receives the nuts H and H' 45 on its ends, said nuts operating in the sockets in the outer ends of the carrier-blocks and bearing against the split washers E, fitting in the bases of said sockets, as shown in Fig. 3.

50 It will be understood in operation the carrier-blocks are screwed into the openings in the harp-prongs from the inner sides of the latter, being suitably adapted at their outer ends to receive a wrench, by which they may be turned as may be desired.

55 Having thus described my invention, what I claim as new, and desire to secure by Letters Patent, is—

1. The improvement in trolleys herein described comprising the harp-prongs provided 60 with the openings threaded for engagement by the screw-stems of the carrier-blocks, the conductor branches having circular heads concentric with the openings in the harp-prongs and fitting against the inner faces of said

prongs, the carrier-blocks provided at their 65 outer sides with the projecting threaded stems passing through the openings in the conductor branches and screwing into the openings in the harp-prongs, the trolley-wheel and its supporting devices carried by the carrier-blocks substantially as set forth. 70

2. The combination in a trolley with the wheel and its supporting devices of the carrier-blocks having means for supporting said devices and provided on their outer sides with 75 projecting threaded stems, the harp-prongs having openings for said stems of the carrier-blocks, and the conductor branches held between the carrier-blocks and the harp-prongs substantially as set forth. 80

3. The combination of the harp-prongs having openings, the carrier-blocks provided on their outer sides with projecting stems fitting in said openings of the harp-prongs, the conductor branches held between the carrier-blocks and the harp-prongs, the trolley-wheel, the shaft supported in the carrier-blocks, the bushing on said shaft and forming a bearing for the trolley-wheel, and the conductor-rings at the opposite ends of said bearing-bushing 90 substantially as set forth. 95

4. In a trolley, the combination with the harp-prongs, of the conductor branches having at their outer ends heads extending adjacent to the inner faces of the harp-prongs, the wheel, and the carrier-blocks supporting a 100 wheel and arranged between the wheel and the heads of the conductor branches. 105

5. The combination of the harp-prongs having openings, the carrier-blocks fitting into 100 said openings from the inner sides of the prongs, the conductor branches held between the carrier-blocks and the inner sides of the prongs, the trolley-wheel, and its supporting devices carried by the carrier-blocks substantially as set forth. 105

6. The combination of the wheel, the harp-prongs having openings for the carrier-blocks, the carrier-blocks having stems held in said openings and provided in their outer ends 110 with recesses for the nuts of the wheel-supporting shaft, the wheel-supporting shaft having the nuts held in the outer recesses of the carrier-blocks, the wheel, and the conductor branches held between the carrier-blocks and 115 the harp-prongs substantially as set forth. 120

7. A trolley having its harp-prongs provided with circular openings and conductor branches having circular heads concentric with said openings combined with the wheel and the carrier-blocks held in the circular openings of the conductor branches and of the harp-prongs, substantially as set forth. 120

8. The combination of the harp-prongs having openings, the conductor branches having 125 at their outer ends heads extending adjacent to the openings in the harp-prongs, the trolley-wheel, and the supporting devices for the

wheel held in the heads of the branches and in the openings of the harp-prongs.

9. The combination of the trolley-wheel, its supporting devices, the harp-prongs having 5 openings receiving said devices, and conductor branches having heads extending adjacent to the openings in the harp-prongs and be-

tween said prongs and the wheel-supporting devices.

JOHN H. WALKER.
